HAIR DRYER

Joseph R. Mango, Midlothian, Ill., assignor to Westinghouse Electric Corporation, Pittsburgh, Pa., a corporation of Pennsylvania

Filed Aug. 22, 1962, Ser. No. 218,720

8 Claims. (Cl. 34—99)

This invention relates to hair dryers, more particularly to portable hair dryers of the domestic type, and has for an object to provide an additional function for such dryers, more particularly, the function of readily drying polish on the finger nails of the user.

Another object of the invention is to facilitate the drying of finger nail polish.

In one form of the present invention, the hair dryer case comprises a base portion and a cover therefor, the two being hingedly joined at one mating edge, whereby the cover may be pivoted to open position to expose the operating controls within the case. In a dryer of this type, much of the mechanism is disposed in the bottom portion of the case and a cover plate conceals and protects this mechanism. Preferably, the cover plate is provided with a raised portion of generally frusto-conical shape, this raised portion providing additional space for the usual motor-blower combination. In accordance with this invention, the inclined conical side wall of the frusto-conical raised portion of the cover plate is provided, in a limited area thereof, with a plurality of openings arranged in two groups through which air is admitted to the blower. These entering air streams are utilized for the drying of finger nail polish.

The two groups of openings constitute the primary (and preferably substantially the only) means of entry of air to the blower below the cover plate. In accordance with usual practice with such devices, this air received by the blower is translated thereby through a passage in the casing, past a heater in such passage by which the air temperature is raised, and the heated air then discharged through an exhaust opening in the casing from whence it is led by a flexible hose to a bonnet or hood worn by the user in a manner well known in this art and hence not described further herein.

Preferably, the two groups of openings above referred to are positioned in adjacent approximately 90° segments of the circular inclined side wall, these 90° segments being preferably located in the front half of the inclined wall and the entire frusto-conical structure is disposed rearwardly of the front of the casing a sufficient distance to provide room at the front of the casing for comfortable support of the users hands while the finger tips are disposed in close proximity to the two groups of openings, the openings of each of the two groups serving to provide for air flow over the finger nails of one hand of the user.

While it will be apparent that the openings of each group may be provided in various shapes and arrangements, in the preferred embodiment herein illustrated the openings of each group are in the form of a plurality of vertical, closely spaced, parallel slots, these groups of slots presenting a pleasing appearance as well as providing the necessary function of permitting entry of air to the blower therebelow. By providing substantially all of the openings to the blower at limited areas of the inclined side wall of the frusto-conical raised portion, the air flow will be concentrated in these limited regions, with the result that there is sufficient flow over the finger nails of the user to insure rapid drying of finger nail polish on the nails.

The above discussed objects and other objects are effected by the invention as will be apparent from the following description and claims taken in connection with the accompanying drawings, forming a part of this application, in which:

2

FIGURE 1 is a perspective view of a hair dryer incorporating the present invention, illustrating the novel use thereof, for drying polish on the finger nails of the user;

5 FIG. 2 is a plan view of the base portion of the hair dryer as shown in FIG. 1, with portions of the structure broken away to more clearly illustrate details of the construction; and,

10 FIG. 3 is a transverse sectional view taken along the line III—III of FIG. 2, looking in the direction indicated by the arrows, portions of the structure being omitted in the interest of clarity.

15 Referring now to the drawings in greater detail, the structure illustrated therein comprises three basic elements; an air translating and heating unit 10, a hood 11 to surround the hair to be dried, and a flexible hose or conduit 12 for conducting heated air from the air translating and heating unit 10 to the hood 11.

20 The present invention relates to the air translating and heating unit 10, this unit comprising a casing 13 including a base 14 and a cover 16 hingedly connected to the latter along one mating edge of the two parts.

25 The base 14 is adapted to rest upon a horizontal supporting surface of any suitable object and is defined by a bottom wall 15 and front, rear and side walls 15a extending upwardly from the bottom wall 15. A cover plate 17 is disposed in approximately parallel spaced relation to the bottom wall 15 and cooperates with upwardly extending walls 15a of the base to provide within the latter a compartment or chamber 18 in which is housed the usual components for a hair dryer of this type. These components include a blower 19 for translating air through the hose 12 to the hood, a motor 20 for driving the blower 19 and heater 21 for heating the translated air prior to its flow through the hose 12. Preferably, the chamber 18 is divided by horizontal partition 22 into an upper portion 23 housing the motor 20 and a lower portion 24 in which is contained the blower 19 and the heater 21. Both the partition 22 and the cover plate 17 are provided with openings 26 and 27 respectively therein for discharge of the heated air from the chamber lower portion 24 to the hose 12.

30 As best shown in FIGS. 1 and 3, the cover plate 17 is provided with an upwardly formed generally frusto-conical portion 30 including a top wall 31 and inclined conical side wall structure 32, although it will be apparent that it could have other shapes.

35 While, in some prior constructions, the motor and blower housing has been provided with a perforated top surface for entry of air, the present invention has the top surface 31 of the raised frusto-conical portion 30 solid without any air admission openings, such admission openings in the herein illustrated construction being provided exclusively in the inclined side wall structure 32 of the frusto-conical portion. Furthermore, as best shown in FIG. 1, these openings for admission of air are in the form of vertical parallel slots 33, disposed in two groups 34 and 35, each group occupying approximately a 90° segment of the inclined wall structure 32. These two groups of slots or 90° segments are preferably located in the front half of the side wall structure 32.

40 Preferably the approximately 90° segments of the wall structure 32 which contain the two groups 34 and 35 of slots 33, are disposed slightly inwardly of the remainder of the inclined wall structure, to more rapidly receive and locate the finger tips of the user, and to prevent accidental slippage of the finger tips circumferentially out of alignment with the groups of openings.

45 As best shown in FIGS. 2 and 3, the partition 22 is provided with a plurality of openings 36 and 37 for flow of air from the slots 33 to the blower 19.

It will be noted that the raised frusto-conical portion of the cover plate 17 is located somewhat rearwardly of the front edge of the base 14 and also is spaced inwardly from the side edges thereof, with the result that the front and right-hand sides or edges of the base serve as a comfortable support for the hands or fingers of the user when utilizing the device for the drying of polish on the finger nails, in the manner clearly illustrated in FIG. 1. From an inspection of FIG. 1, it will be apparent that the user may rest the base portions of the fingers on the edge of the base structure with the tips of the fingers resting on the cover plate 17 adjacent the frusto-conical raised portion 30. Furthermore, it will be apparent that the location of the openings in the two groups above discussed, and the arrangement of these two groups in the front half of the conical inclined surface 32 provides for a natural disposition of the hands while the finger nails are being dried. Consequently, this particular disposition of the two groups of openings is an important feature of applicant's contribution.

By limiting substantially all openings for entry of air to the air translating device to the two restricted areas above discussed, there is provided a concentrated flow of air over the finger nails of the user with the result that the polish thereon is quickly dried.

It will be apparent from the above description of a preferred embodiment of applicant's invention that there is provided apparatus by which the finger nail polish when applied to a user's nails may be quickly and efficiently dried, either at the same time that the hair is dried, or separately.

While the invention has been shown in but one form, it will be apparent that it is not so limited, but is susceptible of various changes and modifications without departing from the spirit thereof.

I claim as my invention:

1. In a domestic hair dryer of the portable type, means for drying polish on the fingernails of the user at the same time that the user's hair is being dried, said means comprising: casing structure including a base, said base being adapted to rest on a generally horizontal supporting surface, a cover plate cooperating with said base to define a chamber, air translating means disposed in said chamber, said cover plate having a generally frusto-conical raised portion whose inclined side wall has a plurality of openings therethrough for entry to the chamber of air to be translated by the air translating means, said openings being readily accessible to finger tips disposed in close proximity thereto, whereby nail polish applied to the nails of such fingers will be rapidly dried by the flow of air thereover just prior to entry of such air through said openings to the air translating means.

2. In a domestic hair dryer of the portable type, means for drying polish on the fingernails of the user at the same time that the user's hair is being dried, said means comprising: casing structure including a base, said base being adapted to rest on a generally horizontal supporting surface, a cover plate cooperating with said base to define a chamber, air translating means disposed in said chamber, said cover plate having a generally frusto-conical raised portion whose inclined side wall has a plurality of openings therethrough for entry to the chamber of air to be translated by the air translating means, said openings being readily accessible to finger tips disposed in close proximity thereto, whereby nail polish applied to the nails of such fingers will be rapidly dried by the flow of air thereover just prior to entry of such air through said openings to the air translating means, said air entry openings being provided in a limited portion only of the periphery of said inclined side wall.

3. In a domestic hair dryer of the portable type, means for drying polish on the fingernails of the user at the same time that the user's hair is being dried, said means comprising: casing structure including a base, said base being adapted to rest on a generally horizontal supporting

surface, a cover plate cooperating with said base to define a chamber, air translating means disposed in said chamber, said cover plate having a generally frusto-conical raised portion whose inclined side wall has a plurality of openings therethrough for entry to the chamber of air to be translated by the air translating means, said openings being readily accessible to finger tips disposed in close proximity thereto, whereby nail polish applied to the nails of such fingers will be rapidly dried by the flow of air thereover just prior to entry of such air through said openings to the air translating means, said air entry openings being provided in a limited portion only of the periphery of said inclined side wall, said openings being the only means for admission of air to the air translating means.

4. In a domestic hair dryer of the portable type, means for drying polish on the fingernails of the user at the same time that the user's hair is being dried, said means comprising: casing structure including a base, said base

20 being adapted to rest on a generally horizontal supporting surface, a cover plate cooperating with said base to define a chamber, air translating means disposed in said chamber, said cover plate having a generally frusto-conical raised portion whose inclined side wall has a plurality of

25 openings therethrough for entry to the chamber of air to be translated by the air translating means, said openings being readily accessible to finger tips disposed in close proximity thereto, whereby nail polish applied to the nails of such fingers will be rapidly dried by the flow of air thereover just prior to entry of such air through said openings to the air translating means, said air entry openings being provided in a limited portion only of the periphery of said inclined side wall, said openings being arranged in two groups.

35 5. In a domestic hair dryer of the portable type, means for drying polish on the fingernails of the user at the same time that the user's hair is being dried, said means comprising: casing structure including a base, said base

40 being adapted to rest on a generally horizontal supporting surface, a cover plate cooperating with said base to define a chamber, air translating means disposed in said chamber, said cover plate having a generally frusto-conical raised portion whose inclined side wall has a plurality of

45 openings therethrough for entry to the chamber of air to be translated by the air translating means, said openings being readily accessible to finger tips disposed in close proximity thereto, whereby nail polish applied to the nails of such fingers will be rapidly dried by the flow of

50 air thereover just prior to entry of such air through said openings to the air translating means, said air entry openings being provided in a limited portion only of the periphery of said inclined side wall, said openings being arranged in two groups, said two groups being provided in adjacent approximately 90° segments of said inclined side wall.

6. In a portable domestic hair dryer, means for drying polish on the fingernails of the user at the same time that the user's hair is being dried, said means comprising: casing structure including a base having a bottom wall

60 and upstanding side wall structure, a cover plate cooperating with said base to define a chamber, a blower and an electric motor therefor housed in said chamber, the cover plate being disposed in generally parallel relation to the base bottom wall and having a raised portion including a substantially flat top wall and an intermediate

65 side wall structure connecting said top wall with the remainder of the cover plate, said side wall structure having two groups of openings therethrough for entry of air to the chamber for cooling said motor and for translation by the blower, said motor being disposed above the

70 blower and extending within the raised portion of the cover plate, said two groups of openings providing for concentrated flow of air at restricted locations for rapid drying of nail polish on a user's fingers when the fingers are positioned adjacent said groups of openings, each

group of openings comprising a plurality of parallel, closely spaced, vertical slots of insufficient width to permit entry of the user's fingers.

7. In a portable domestic hair dryer, means for drying polish on the fingernails of the user at the same time that the user's hair is being dried, said means comprising: casing structure including a base having a bottom wall and upstanding front, rear and side walls, a cover plate cooperating with said base to define a chamber, a blower and an electric motor therefor housed in said chamber, the cover plate being disposed in generally parallel relation to the base bottom wall and having a raised portion including top wall and an intermediate side wall structure connecting said top wall with the remainder of the cover plate, said side wall structure having two groups of openings therethrough for entry of air to the chamber for translation by the blower therein, said two groups of openings providing for concentrated flow of air at restricted locations for rapid drying of nail polish on a user's fingers when the fingers are positioned adjacent said groups of openings, said two groups of openings being disposed in adjacent approximately 90° segments of said intermediate side wall structure and said adjacent 90° segments lying in the front half of said intermediate side wall structure.

8. In a portable domestic hair dryer, means for drying polish on the fingernails of the user at the same time that the user's hair is being dried, said means comprising: casing structure including a base having a bottom wall and upstanding side wall structure, a cover plate cooperating with said base to define a chamber, a blower and an electric motor therefor housed in said chamber, the cover plate being disposed in generally parallel rela-

tion to the base bottom wall and having a raised portion including a top wall and an intermediate side wall structure connecting said top wall with the remainder of the cover plate, said side wall structure of the cover plate having a group of openings therethrough for entry of air to the chamber for translation by the blower therein, the structure defining said chamber having an additional opening therethrough for discharge of translated air from the chamber to the user's hair, said group of openings providing for concentrated flow of air at a restricted location for rapid drying of nail polish on a user's fingers when the fingers are positioned adjacent said group of openings, said openings being of insufficient size to permit entry of said fingers.
